CLAIM

The ornamental design for a footwear outsole, as shown and described.

DESCRIPTION

The present application is related to U.S. Design patent application Ser. No. 29/658,604, entitled Footwear Outsole, U.S. Design patent application Ser. No. 29/658,603, entitled Footwear Outsole, and U.S. Design patent application Ser. No. 29/658,615, entitled Footwear Outsole, all filed concurrently herewith, the entire disclosures of which are incorporated herein by reference.

FIG. 1 is a perspective view of the footwear outsole according to my design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines of even length show environment and portions of the footwear outsole that form no part of the claimed design. The broken lines of uneven length define the bounds of the claimed design, and also form no part thereof.
